Specification for Design.

Patented Mar. 9, 1915.

Application filed December 31, 1914. Serial No. 879,977. Term of patent 3½ years.

To all whom it may concern:

Be it known that I, ALEXANDER J. FRANKLAND, a citizen of the United States of America, residing at Tropico, in the county of Los Angeles, State of California, have invented a new, original, and ornamental Design for a Spoon, of which the following is a specification, reference being had to the accompanying drawings, forming part hereof, and in which—

Figure 1 is a front view of the spoon illus-

trating my new design; Fig. 2 is a side view of the spoon; and Fig. 3 is a sectional view taken on the line 3—3 of Fig. 1.

I claim:

The ornamental design for a spoon, as shown.

ALEXANDER J. FRANKLAND.
